UNITED STATES PATENT OFFICE.

WILLIAM HARRY BRASIER, OF CORPUS CHRISTI, TEXAS.

LOCK BOX.

Application filed March 26, 1923. Serial No. 627,920.

To all whom it may concern:

Be it known that I, WILLIAM HARRY BRASIER, a citizen of the United States, residing at Corpus Christi, in the county of Nueces and State of Texas, have invented a new and useful Lock Box, of which the following is a specification.

This invention aims to provide a simple means whereby it will be impossible for a person to remove a full bottle of milk or the like from a receptacle without supplying an empty bottle, and whereby it will be impossible to remove the empty bottle without supplying a full bottle, an equitable arrangement between the customer and the milk dealer thus being brought about, and a full bottle of milk or the like being rendered reasonably secure against theft.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention; Figure 2 is a section on the line 2—2 of Figure 1; Figure 3 is a section on the line 3—3 of Figure 1; Figure 4 is a section taken in a plane at right angles to the cutting planes in Figures 2 and 3; Figure 5 is a section on the line 5—5 of Figure 4; Figure 6 is a section on the line 6—6 of Figure 4.

In carrying out the invention, there is provided a receptacle 1 which is open at the front, the receptacle having a hollow partition 2 forming compartments which are located side by side, the partition comprising a front 3 and sides 4, the sides being united by a connection 5. The sides 4 of the partition 2 are provided on their rear edges with tubular guides 6.

A receptacle 1 is provided with front doors 7, each including a plate 8 supplied along its vertical edges with inwardly extended flanges 9, each door having an inwardly projecting bottom or arm 10 hav-

ing upstanding flanges 11 overlapped on the flanges 9 of the plate 8. The numeral 12 marks a support, in the form of a rod, mounted in the sides of the receptacle 1 and in the partition, the rod passing through the overlapped portions of the flanges 11 and 9 of the doors 7, the doors being thus mounted, at points adjacent to their lower ends, for vertical swinging movement, toward and away from a closed position. Each plate 8 carries an inwardly projecting bottle hanger 14, there being handles 15 on the outside of the door plate 8, securing elements 16 serving to unite both the handles 15 and the hangers 14 with the door plates. Inwardly offset plates 17 are connected at 50 to the door plates and extend downwardly to the bottom portions 10 of the doors. A short rod 18 is mounted in the partition 12, the ends of this rod constituting stops, which, cooperating with the flanges 11 of the doors limit the movement of the doors, as they pass to an open position.

A rod or support 19 is mounted in the ends of the receptacle 1 and in the partition 2, and on the rod, vertically swinging latches 20 are mounted, downward swinging movement of the latches being limited by a stop rod 21 carried by the partition 2. As shown best in Figure 5 a horizontal shaft 22 is mounted to rock in the front 3 of the partition 2 and in the member (Figure 3) of the partition. A detent 23 is secured to the forward end of the shaft and is adapted to overlap either of the doors 7 to hold either door closed. An arm 24 is secured to the rear end of the shaft 22 and swings in engagement with the connection 5 of the hollow partition 2. Along its longitudinal edges, the arm 24 is supplied with forwardly extended projections 25, which, operating with the partition 2, limit the swinging movement of the arm 24 to the right or to the left (Figure 4). The arm 24 has an arcuate opening 26, and there are seats 27 in the arm, at the ends of the opening.

Locking members 28, such as rods, are mounted for vertical right line reciprocation in the guides 6. At their lower ends, the locking rods 28 are supplied with laterally extended fingers 29 (Figure 4) extended beneath the arms or bottom portions 10 of the doors 7. At their upper ends, the locking rods 28 are equipped with rear-

wardly extended projections 30 (Figure 3) operating in the arcuate opening 26 of the arm 24 and adapted to cooperate, one at a time, with the seats 27. The upper ends of the locking rods 28 are surrounded by helical compression springs 31 the upper ends of the springs abutting against the projections 30, and the lower ends of the springs abutting against the upper ends of the guides 6.

Suppose that both of the doors 7 are closed, and that a bottle is held in one compartment by one of the hangers 14 as indicated in dot and dash line in Figures 4 and 5. Suppose that the detent 23 overlaps the door 7 of the compartment wherein the bottle is located, as shown in Figure 1. When the detent 23 is in the position shown in Figure 1, the arm 24 is in the position depicted in Figure 4, movement of the arm 24 to the right, in Figure 4 having been limited by the engagement between one projection 25 on the arm and the partition 2. The projection 30 on one locking rod 28 is aligned with one of the seats 27, and the corresponding projection on the other locking rod is received in the arcuate opening 26 of the arm, as shown in Figure 4, both of the rods 28 being held in a lowered position, and the springs 31 being compressed, by the action of the arms 10 of the doors 7 on the fingers 29 at the lower ends of the rods 28. The bottle has raised the latch 20 of the compartment in which the bottle is located, but the latch 20 of the empty compartment has not been raised by the action of a bottle and lies in the path of the arm 24. The result is that the shaft 22 cannot be rotated, and a person cannot move the detent from the locked position of Figure 1, open the door of the compartment in which the bottle is located, and remove the bottle.

Suppose that a person opens the door 7 of the empty compartment to insert a bottle 45 therein. As soon as the door 7 of the empty compartment is opened, the arm 10 of that door no longer holds the corresponding rod 28 down, and the rod rises, under the action of its spring 21, the projection 30 of the said 50 rod entering one seat 27 of the arm 24, the said seat being positioned for the reception of the projection, as shown in Figure 4. The result is that although the door of the empty compartment has been opened, one cannot 55 thrust the hand into the empty compartment, raise the latch 20 of that compartment, set the arm 24 free, move the detent 23 to unlocked position, open the door of the compartment in which the bottle is located, and 60 remove the bottle.

Whilst the door 7 of the empty compartment is open, the operator places a bottle 65 on the hanger 14 of that compartment and closes the door, the door being carried into the compartment, which, for convenience in

description, may still be called the "empty" compartment. When the door of the "empty" compartment is closed, the bottle in the "empty" compartment raises the corresponding latch 20 and sets the arm 24 free, the part 10 of the door of the "empty" compartment cooperating with the corresponding finger 29, to draw the rod 28 downwardly out of the seat 27, into the position delineated in Figure 4, the arm 24 thus being set free, whereby the detent may be swung to the right in Figure 4, the left hand door being opened, and the first specified bottle being taken out, the bottle which the operator has introduced into the receptacle being securely housed until the cycle of operations above outlined has been repeated.

What is claimed is:—

1. In a device of the class described, a receptacle, bottle-carrying doors movably mounted on the receptacle, a detent adapted to engage either door to hold the same closed, a member movable on the receptacle and carrying the detent, latches movable on the receptacle and cooperating with said member to hold the detent in locked position with respect to either door, the latches being so located that they may be moved to released position by a bottle on either door, and locking means cooperating with said member to hold the detent in locked position with respect to either door, each door comprising a part cooperating with one locking means to release the same as the door is closed.

2. In a device of the class described, a receptacle, bottle-carrying doors movably mounted on the receptacle, a detent adapted to engage either door to hold the same closed, a member movable on the receptacle and carrying the detent, latches movable on the receptacle and cooperating with said member to hold the detent in locked position with respect to either door, the latches being so located that they may be moved to released position by a bottle on either door, locking elements mounted for right line reciprocation on the receptacle, spring means cooperating with the locking elements to cause them to engage with said member, thereby to hold the detent in locked position, one of the doors embodying means for moving the latches to released position with respect to said member, when the doors are closed.

3. In a device of the class described a receptacle, bottle-carrying doors movably mounted on the receptacle, a shaft mounted to rock on the receptacle a detent carried by the shaft and adapted to engage either door to hold the same closed, an arm on the shaft, latches movable on the receptacle and cooperating with the arm to hold the detent in locked position with respect to either door, the latches being so located that they may be moved to released position by a

bottle on either door, and locking means co-operating with the arm to hold the detent in locked position with respect to either door, each door comprising a part cooperating with one locking means to release the same when the doors are closed.

In testimony that I claim the foregoing as

my own, I have hereto affixed my signature in the presence of two witnesses.

WILLIAM HARRY BRASIER.
